UNITED STATES PATENT OFFICE.

MARTIN SAND, OF TURNBRIDGE, NORTH DAKOTA.

CULTIVATOR.

Application filed July 16, 1921. Serial No. 485,281.

To all whom it may concern:

Be it known that I, MARTIN SAND, a citizen of the United States, residing at Turnbridge, in the county of Pierce and State of North Dakota, have invented new and useful improvements in Cultivators, of which the following is a specification.

The object of this invention is to provide a cultivator capable of following after a twenty-shoe drill, to stop drifting and to kill weeds.

With this and other objects in view, as will be hereinafter more fully pointed out, reference will be had to the accompanying drawings forming a part of this specification and wherein like numerals of reference designate corresponding parts throughout the several views, in which:

Fig. 1 is a top plan view of the invention complete, with the single exception that the draft tongue is broken off,

Fig. 2 is a view in side elevation of the invention, with the draft tongue broken off,

Fig. 3 is a vertical sectional view of the front wheel portion of the invention,

Fig. 4 is a top plan fragmentary view taken on the plane 4—4 of Fig. 2, and

Fig. 5 is a perspective view of the combined locking and guiding handle.

Referring to the accompanying drawing, reference numeral 1 designates the front wheel, 2 the rear wheels, 3 the rear axle attached suitably beneath a rectangular body frame which is composed of two double-timber side beams 4, connected at their front ends by front beam 5 and at their rear ends by rear beam 6. The front frame beam 5 together with the forward ends of the side beams 4 rest upon a sill 7, (see Fig. 2) and this sill, in turn, rests upon the main cultivator tooth carrying beam, which extends considerably beyond each rear wheel on both sides of the main frame.

Extending centrally of the main body frame is a center sill or beam 8, secured at its rear end of the rear frame member 6, to the axle 3, and to the front frame member 5, and thence extends forwardly as one piece, or as a separate piece 9. In the drawings, the parts 8 and 9 are separate, being connected by upper and lower straps 10, bolted through and through as at 11, and advantage may be taken of this construction to secure the seat 12 in place, as illustrated in detail in Fig. 3. This part 9 is arched and terminates in a head 14 in which

is journaled the stem 15 of the front wheel fork 16. The front wheel 1 is journaled in the lower ends of the fork furcations, and is turned to guide the cultivator by means of a handle 17 or draft tongue 18 as the case may be as will be later explained. The draft tongue 18 rests upon the frame head 14 and swivels on the stem 15, being held from vertical movement on the stem by a collar 19 secured to the stem by pin 20. The upper end of the stem 15 is squared and the said handle lever 17 is centrally fulcrumed at 21 thereto, and its forward end is provided with a locking tooth or pin 22 extending downwardly and adapted to be inserted or withdrawn from a recess 24 formed in the draft tongue 18, so that the front wheel may be turned for guiding by means of the handle lever 17 solely, or by means of the draft tongue through the handle lever 17 interlocked at 22—24 therewith. The front fork is provided on each side with a foot rest 25, which also serves as an aid in manual guiding.

Extending transversely across the machine at the front thereof is a guide member, looped at its center 27 to encircle a pin 28 and extending outwardly as outriggers on opposite sides thereof and these outriggers have their outer ends bent downwardly as at 29, in Fig. 2, and their extreme lower ends formed with eyes 30 and through these eyes extend the forward ends of the draft rope 31. The central portion of this rope passes across in front of the frame beam 5 which latter has at its ends the guide pulleys 32 through which also the draft rope 31 passes. At the free forward ends, the draft rope is equipped with trees 32, one on each side of the machine, and while these are shown as hanging down in full lines in Figs. 1 and 2 it will be understood that in operation, they assume the dotted line position of both Figs. 1 and 2, and any inequalities in draft may be compensated for by the draft rope passing through the pulleys from one side to the other according to the amount of pull on one side or the other.

The main cultivator tooth carrying beam 40 on its rear side is provided with eyes 41 spaced at regular intervals and through their eyes having the pintle rod 42 extending. The outer ends of this rod 42 are bent upwardly as at 42' and secured in the model in cut out portions 43, see Fig. 2, by pins

44, though obviously the terminal ends of the pintle rod 42 may be simply headed or equipped with terminal nuts, or otherwise terminated, so as not to be easily displaced.

5 The cultivator tooth bars 45 are provided at their forward ends with sheet metal loops or hinge barrels 45' which extend between the eyes 41 and receive the pintle rod 42. These barrels 45' are formed by doubling a 10 piece of sheet metal so that the central or doubled portion forms the barrel and the two free ends 46 are inserted into kerfs 47 formed in the forward ends of the cultivator tooth bars. At their rear ends, the tooth bars 15 are provided with suitable teeth, of selected form. Beneath the tooth bars are two lifting bars 50 mounted for swinging movement on brackets 51 pivoted on said pintle rod 42. One such lifting bar 50 is 20 provided for each side of the machine as indicated by the dotted lines adjacent the rear of the seat in Fig. 1, and each said bar 50 is provided with an operating lever 52, which in the Fig. 2 position occupies a position 25 at the rear of the double detent 53, or in the Fig. 1 position occupies a position at the front of this detent 53, thereby positively holding the tooth bars elevated or depressed.

30 Since this cultivator is designed to follow a twenty-tooth grain drill, provision must be made for cultivating nineteen spaces between the drilled or plant rows. Teeth are provided to cultivate sixteen of these rows 35 or spaces, two of the tooth bars and their teeth being obscured in Fig. 1 by the frame beams 4 under which these are located. For cultivating the remaining of the nineteen spaces, or to be specific, the remaining three 40 spaces or rows, provision is made whereby the two rear and single front wheels occupy these spaces or rows and by their rolling action serve to prevent drifting and to depress the spaces in which they roll.

45 It is preferable to adjust the two center drills of the drilling machine that this cultivator follows so that the space between the center drilled rows will be greater and when the young plants come up, be more easily 50 distinguished so that the operator of the cultivator will have no trouble in always causing the front or center wheel to follow the center space row previously drilled.

55 In operation, the driver occupies the seat 8-9 with his feet on the foot rests 25. The rear end of the guiding handle or lever 17 is elevated so that its nose 22 engages in notch 24 of the draft tongue to cause the 60 front wheel to turn with the draft tongue according to the direction in which the draft animals or tractor (if one is employed) travels. If it becomes necessary for any 65 reason to guide the machine independently of the draft tongue, or to allow the draft

tongue independent swinging movement, the rear end of the guiding handle 17 is depressed to bring its nose 22 out of the recess 24 of the draft tongue and permit independent movement of the draft tongue and manual steering movement of the front wheel.

It is needless to set forth the specific conditions under which locking or releasing of the steering head and draft tongue might be desirable, since the same will be apparent to all farmers, nor does it seem to be necessary to state that the structural details of the machine shown in the drawings are those of a model and that the same may be modified along more conventional lines, except in the details claimed as part or substance of the invention.

Having described the invention, what is claimed as new and useful is:

1. A cultivator comprising a frame, a steering device swiveled to the frame, a vertically swinging lever pivoted to the upper portion of the steering device, a draft appliance swiveled to the upper portion of the steering device, and cooperative means carried by the lever and draft appliance whereby the said lever may be interlocked with the draft appliance or free thereof to permit steering through the draft appliance or manually.

2. A cultivator comprising a frame, a fork swiveled in the front end portion of the frame, a wheel journaled in the fork, a lever pivoted on the upper end portion of the fork, a draft tongue swiveled on the upper end portion of the fork, means for interlocking the lever with the draft tongue to permit steering by the draft tongue when these parts are engaged or manually through the lever when these parts are disengaged, a seat on the frame, and foot rests on the furcations of the fork.

3. A cultivator comprising a frame, a steering head swiveled in the frame, a wheel journaled in the steering head, a hand lever secured to the steering head by which the steering head and wheel may be turned for guiding action, a draft appliance swiveled on the head adapted to be interlocked with the said lever when it is desired to turn the steering head and wheel by the draft appliance, a pair of trees, one on each side of the steering head, and a flexible draft member attached at its ends to each tree and extending through a guide member from one side to the other of the cultivator.

In testimony whereof I have hereunto set my hand in presence of two subscribing witnesses.

MARTIN SAND.
